(57) CLAIM

We claim the ornamental design for a gas range oven, as shown and described.

DESCRIPTION

FIG. 1 is a front perspective view of a gas range oven showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom thereof.

The broken lines in the figures show portions of the gas range oven which form no part of the claimed design.
